UNITED STATES PATENT OFFICE

JAMES G. ROSS, OF SEATTLE, WASHINGTON

MOP WRINGER

Application filed August 22, 1931. Serial No. 558,803.

This invention relates broadly to mops and more specifically to combined mops and wringers and has for an object to provide a pair of rollers which coact with a cross pin in securing the mop cloth, one of the rollers being equipped with a crank handle to permit of the rollers being rotated to feed the mop cloth therebetween and wring out the same as often as desired.

A further object of the invention is to provide a front guard over which the mop cloth is trained, and which holds the mop cloth from working back between the wringing rollers when in use and which also positions the metal frame of the mop head from touching and scratching the floor while in use.

A further object is to provide a light, strong and durable device of this character which will be formed of a few simple parts which are inexpensive to manufacture and which will not easily get out of order.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification.

Figure 1 is a longitudinal sectional view through a mop constructed in accordance with my invention, with parts in elevation, and

Fig. 2 is a plan view of the mop, with the mop cloth removed.

Referring now to the drawing in which like characters of reference designate similar parts in the various views, the mop head comprises a pair of parallel metal plates 10 which may be of any desired shape but, preferably, are of the shape shown in Fig. 1, the rear ends of the plates being directed inwardly toward each other to provide spreaders 11 which space the plates 10 the required distance apart. The extremities of the spreaders 11 are connected by a ferrule 12

which receives the mop handle 13. The ferrule is, preferably, secured to the mop handle 13 by means of a bolt 14.

In further carrying out the invention, I provide a pair of superposed rollers 15 and 16 which, preferably, are formed of rubber, and, preferably, the lower roller is set forwardly slightly beyond the upper roller 15. The rollers are provided with metal rod shafts 17, the ends of which are rotatably mounted in suitable openings formed in the spaced plates 10 of the mop head. The shaft of the upper roller is extended outwardly beyond one of the side plates 10 and is equipped with a crank 18 having the usual grip 19.

The mop cloth 21, of any preferred type, is doubled upon itself and the bight or loop thereof passed between the rollers 15 and 16 and carried rearwardly therebeyond where it is passed over a bar 22 terminally secured to the side plates 10 between and to rear of the rollers. The bar 22 is threaded at one end to receive a nut 23 which may be tightly screwed up against the adjacent side plate 10 of the mop head to draw the side plates together against the ends of the rollers and thereby tighten up the rollers to prevent too free rotation thereof, as will be understood. By simply unscrewing the nut 23, the rod 22 may be removed from the mop head to permit removal of the mop cloth 21 or application of the same as often as desired.

To prevent the mop cloth from working back between the rollers during the mopping operation, a transverse arcuate metal guard 24, preferably formed integral with the head or otherwise secured thereto, is provided at the front lower ends of the side plates 10 below and in front of the lowermost wringing roller 16.

The mop cloth 21 is passed over the front side of the guard 24 and extends rearwardly underneath the guard. During the mopping operation, the guard 24 functions as a stop to prevent the loop or bight in the mop cloth working rearwardly between the wringing rollers, and also performs the additional function of preventing the metal side plates 10 from touching and scratching the floor.

In operation, when it is desired to wring the mop, it is simply necessary to rotate the crank handle 18 forwardly to feed the mop cloth rearwardly between the wringing rollers and simultaneously compress the same to squeeze out the water. Retrograde rotation of the crank handle feeds the mop cloth forwardly between the wringing rollers, during which operation the squeezing of the mop cloth is repeated. Thus, the mop cloth may be fed back and forth between the wringing rollers as often as desired to wring out the mop thoroughly.

From the above description it is thought that the construction and operation of my improved mop and wringer will be fully understood without further explanation.

Having thus described the invention, I claim:

20. 1. A combined mop and wringer comprising spaced side plates, spreaders at the rear ends of the side plates directed toward each other and terminating in a ferrule, a handle secured in said ferrule, a pair of superposed wringing rollers carried by said side plates, a crank handle attached to one of said rollers, a bar extending between said side plates in rear of said wringing rollers, a mop cloth doubled upon itself and having the bight passed rearwardly between said wringing rollers and engaged around said bar, and an arcuate guard carried by said side plates below and in front of the lowermost wringing roller over the front side of which said 35 mop cloth is directed and from thence carried rearwardly underneath said guard, the guard having the dual function of preventing the mop cloth working back between the wringing rollers and elevating the side plates so as to prevent the side plates touching and scratching the floor.

2. A combined mop and wringer comprising spaced side plates, a handle operatively connected to the rear ends of the side plates, 45 said side plates being resilient, a pair of superposed wringing rollers carried by the side plates, one of the rollers being equipped with a crank handle, a transverse bar terminally secured to the side plates in rear of the wringing rollers, a nut threaded on one end of the bar and adapted to be tightened against the adjacent side plate for drawing the side plates together into engagement with the ends of the wringing rollers to prevent too free 55 rotation of said wringing rollers, a mop cloth doubled upon itself and having the bight passed rearwardly between said wringing rollers and engaged around said bar, and a transverse guard carried by said side plates 60 below and in front of the lowermost wringing roller over the front face of which said mop cloth is passed and from thence directed rearwardly underneath the guard to extend rearwardly between and underneath said side 65 plates, the guard performing the dual func-

tion of preventing the mop cloth from working back between the wringing rollers and also elevating the side plates to prevent the same touching and scratching the floor.

In testimony whereof I affix my signature. 70
JAMES G. ROSS. [L.S.]
